DISPLAY BOX FOR ELECTRIC RAZORS AND THE LIKE

Carl R. Daley, South Natick, Mass., assignor to Fanning Manufacturing Company, Needham Heights, Mass., a corporation of Massachusetts

Application March 7, 1958, Serial No. 49,936

Term of patent 7 years

(Cl. D80—5)

Fig. 1 is a perspective view of a display box for electric razors and the like showing my new design;

Fig. 2 is a side elevational view thereof;

Fig. 3 is a plan view thereof;

Fig. 4 is a front elevational view thereof;

Fig. 5 is a perspective view similar to that shown in Fig. 1 but with a portion of the box rotated to open position; and

Fig. 6 is a vertical section of Fig. 5.

I claim:

The ornamental design for a display box for electric razors and the like, as shown.
